(57) **CLAIM**

The ornamental design for a docking station for a vehicle diagnostic tablet, as shown and described.

DESCRIPTION

FIG. 1 is a front perspective view of the docking station shown in an environment of use holding a vehicle diagnostic tablet;

FIG. 2 is a front perspective view of the docking station of FIG. 1;

FIG. 3 is a front elevation view of the docking station of FIG. 2;

FIG. 4 is a rear elevation view of the docking station of FIG. 2;

FIG. 5 is a left side elevation view of the docking station of FIG. 2;

FIG. 6 is a right side elevation view of the docking station of FIG. 2;

FIG. 7 is a top plan view of the docking station of FIG. 2; and,

FIG. 8 is a bottom plan view of the docking station of FIG. 2.

The broken lines depict environmental subject matter only and form no part of the claimed design.

1 Claim, 8 Drawing Sheets
